[57] CLAIM

The ornamental design for a refill container for use
when spraying liquids, as shown and described.

DESCRIPTION

FIG. 1 is a front elevational view of the refill container
for use when spraying liquids showing my new design;
FIG. 2 is a rear elevational view thereof;
FIG. 3 is a left side elevational view thereof;
FIG. 4 is a right side elevational view thereof;
FIG. 5 is a top plan view thereof; and,
FIG. 6 is a bottom plan view thereof.

*FIG. 1**FIG. 2**FIG. 3*

FIG. 4

FIG. 5

FIG. 6
